BOTTLE LOCK

Lester P. Barlow, Stamford, Conn.

Application January 15, 1935, Serial No. 1,836

13 Claims. (Cl. 215—32)

This invention relates to a bottle intended to insure the genuineness of its contents at the time of the purchase of the bottle and its contents by the ultimate consumer. Bottles of this 5 general class have particular utility at the present time in the marketing of wine, whiskey and other spirituous liquors.

Because of the activities of bootleggers, who have operated to defraud the United States Government of taxes by utilizing old bottles, particularly bottles which have contained some of the better and more widely advertised brands of spirituous liquors, which they refill and seal with counterfeit seals, and because of the consequent defrauding of legitimate distillers of good whiskies and the makers of other spirituous liquors, considerable inventive effort has been directed toward the discovery of a bottle which would completely foil the bootlegger.

20 These efforts have been mainly along two lines: in the field of what are known as non-refillable bottles, that is, bottles which retain their identity but are supposed to be so designed that when the contents are removed they cannot be refilled, 25 and in the field of what I prefer to term "non-repackeageable" bottles, that is, bottles which when once opened may never again be refilled and resold as an original package because, in the act of opening the bottle, an integral portion of the 30 bottle must be destroyed.

Because of the fact that bottles are necessarily made of glass which, even when annealed by the most modern annealing methods, still has extensive internal strains, attempts heretofore 35 made to provide a satisfactory non-repackeageable bottle, particularly for use in the marketing of spirituous liquors, have proved to be abortive. These attempts to design a non-repackeageable bottle, which necessarily involve a breaking away

40 from the bottle structure of what has been an integral portion thereof, have been of such design and character that splintering or slivering of the glass practically always occurs in the breaking operation and that, in addition, there 45 is apt to appear upon the part of the bottle which remains, an extremely sharp and frequently jagged edge likely to injure the hand of the user. Also, the breaking could not be controlled so as 50 to follow a definite line of cleavage which could be depended upon. It will be readily appreciated that in this art the breakage must be certain and along definite lines in each case. Even one bad break in five thousand bottles would make a particular type of bottle unsatisfactory. For this

reason, there is not on the market today a single non-repackeageable bottle as herein defined.

Even in those cases where the bottles have been so designed that the slivers or splinters of glass would not be likely to remain in such position as to appear later in the drink itself, no attempt has been made to eliminate automatically the danger due to the leaving of sharp and/or jagged edges on the bottle itself. Moreover, it is obvious that the splintering or slivering 10 of the glass in the act of opening the bottle, with the consequential scattering of the splinters or slivers about the point of opening, is objectionable, as anyone will appreciate who has undertaken to locate glass splinters or slivers on floors 15 or rugs. This is especially true when bottles are opened in private homes, as is so commonly the practice under the present methods of vending spirituous liquors.

A further reason why so many attempts heretofore to make non-repackeageable bottles have proved to be abortive is that their designs have been impracticable from the standpoint of economical manufacture in bottle making plants.

The present invention aims generally so to design and construct a bottle of the non-repackeageable type as to eliminate the objections in part above recited which have rendered the attempts heretofore made to solve the non-repackeageable bottle problem abortive.

More particularly the invention aims to provide a bottle, so constructed as to require the breaking from the bottle of an integral portion thereof to obtain access to its contents, which is also so designed and constructed that the breaking act may be performed with consistency with the practical elimination of liability to the formation of splinters or slivers.

The invention further aims to insure that in the rare event that slivers or splinters should be 40 formed there will be no scattering of these about the point of the bottle opening and no danger of their ever either entering the bottle or any container into which its contents may be poured nor of their in any way injuring the one who opens 45 the bottle or anyone who thereafter uses it.

In addition to providing for a splinterless breaking off of the removable part of the bottle and for insurance against scattering splinters in the rare event of a defectively annealed bottle not responding to the normally to be expected rupturing action, the invention aims to insure that there will be left exposed on the opened bottle no sharp and/or jagged edges which could in any way injure the user of the bottle.

55

In addition to providing a bottle requiring the destruction of a portion thereof to obtain access to its contents, which will overcome the objections to bottles of this type heretofore designed, the invention aims also so to improve the design of a non-repackagable bottle as to facilitate both its manufacture and its filling. These important features of the invention will be referred to incidentally in connection with the following listing of the more distinctive features of the invention.

In the manufacture of bottles, after the bottle is molded into its final shape, the entire bottle, including the neck, is thoroughly annealed. This annealing operation results in a substantially uniform distribution of the surface strain over the entire surface of the bottle, both inside and out. From this it will be apparent that if any weakening of the structure is to be provided for the purpose of directing a fracture, it will not be effective to prevent splintering if the weakening slot, or depression, or hole, or whatever is designed for this purpose, be molded into the structure during the molding of the bottle, since its surfaces will be subjected to the same annealing operation and therefore will have distributed over them their proportion of the surface tension. This has been one of the causes of the failure of non-repackagable bottles heretofore designed.

I have discovered that by cutting a slot in the bottle neck after the bottle has been completed, including the annealing operation, and preferably causing this slot to intersect both the inner and outer surfaces of the bottle neck, I initiate a plane of cleavage, or sometimes two planes of cleavage because, of course, the slot has substantial width, which insure the rupture of the upper part of the bottle neck from the part to remain on the bottle when opened with substantial freedom from splintering or slivering. In fact, splintering or slivering is an extremely rare occurrence. When I speak of two planes of cleavage I am referring to the fact that when the sides of the slot are spread to effect the rupture of the removable portion of the neck from the part which remains integral with the bottle as, for example, by the use of the key herein-after more specifically to be described, the plane of cleavage may coincide with the upper wall of the slot at one end and with the lower wall of the slot at the other end. However, the fact that there is a slight initial spacing of the two planes of cleavage does not appear to affect the splinterless character of the rupturing operation since the entire section of the neck appears to be sufficiently weakened so that the slight offset of the two planes is taken care of by a minute offset fracture where the two fractures meet on the opposite side of the neck, the rupturing being progressive.

As above suggested, the slot cut into the bottle neck to initiate and define the location of the cleavage plane is of such a nature that when a spreading force is directed against the walls thereof it will effect the rupturing of the removable part of the bottle neck. I find that a very desirable method of applying this spreading force to the walls of the slot to secure the desired uniformity of rupturing action is to use a tool exerting a cam action on the slot as, for example, a key having one of its dimensions such that it will readily enter the slot and its dimension, when turned, such that it effects the desired spreading action. I have found also that by shaping the

slot in a particular manner I can first apply the rupturing force to a tapering section of the neck at each end of the slot, and then to the full cross section of the neck. This facilitates greatly the obtaining of a rupturing action rather than a sharp snapping and breaking of the neck. 5

The cleavage plane defining and initiating slot being preferably cut through both surfaces of the bottle neck so that it makes an opening through the neck wall, it is desirable, in order that the bottle may be adapted for filling by the modern vacuum filling processes, that this opening be closed in some manner at the time the bottle is to be filled.

An important feature of the invention is the utilization of a resilient flexible covering member for performing at least three important functions:

First, by its contracting action, when the bottle is opened by removing the upper part of the neck after rupturing, to shield the part of the rupture remaining on the bottle so that it will not come into contact with the hands of the user; secondly, to cover the area of severance and to maintain the severed portion in position after severance; and in the rear event that slivers or splinters may break off in the rupturing operation, to cover and confine these against movement away from the bottle and against contact with the hands of the user, and, thirdly, while still in position on the bottle before rupturing of the removable portion of the neck, to serve as a closure for the slot to permit vacuum filling of the bottle, to keep dirt and dust out of the slot and to act as a valve to relieve any pressure that might form in the enclosed space above the bottle stopper hereinafter to be referred to. 35

It will be obvious that any internal pressures being exerted on the removable part of the bottle neck at the time rupturing pressure is exerted thereon will tend to interfere with the uniformity of the rupturing or ripping action and therefore might cause undesirable shattering.

It will be noted also that this covering member is useful in other ways. For example, by reason of its being located over the rupturing slot it is necessary that the key be pushed through the covering member to enter the slot which insures wiping of the key both as it is inserted and as it is withdrawn, the covering member being preferably formed of some highly resilient material like rubber. 45

The removable portion of the bottle neck, to which attention has been particularly directed hereinabove, preferably forms the major part 55 of an enclosing chamber for the bottle stopper proper, the bottle stopper remaining in the bottle when the removable part of the neck has been broken away from the bottle but being then readily removable by hand so that the user may open and close the bottle at will until the contents are removed.

Important features of the invention reside in the construction and arrangement of the bottle stopping means to permit the removal of the upper part of the bottle neck without interference therewith and to permit ready utilization of the bottle stopper after the removable part of the neck has been broken off. 65

It is desirable, from the standpoint of convenient manipulation of the bottle stopper, that it be located above the plane of fracture of the removable part of the bottle neck from the bottle. To provide for this in a bottle construction that is economical to manufacture and conven- 70 75

ient to assemble, I provide a hollow cork extending through a restricted portion of the bottle neck and a stopper fitting into this hollow cork, this hollow cork preferably extending above the 5 restricted portion of the neck into the enlarged chamber provided by the removable portion of the neck and there being reinforced by a metal ferrule surrounding it so that it cannot be ruptured or otherwise injured by the act of inserting and removing the stopper. The metal ferrule also protects it against injury during the 10 operation of breaking off the removable part of the bottle neck. In addition the ferrule forms a limit surface against which the resilient covering member may contract as the upper severed neck portion is removed, and for the purposes 15 already indicated and hereinafter emphasized.

Important features of the invention are the arrangement of this cork extension and its surrounding ferrule in a chamber formed by a removable part of the bottle neck which has its inner wall so spaced from the cork ferrule that the rupturing operation ordinarily will not cause engagement of the removable part of the bottle 20 neck with the ferrule; the location of the rupture-initiating slot at a point sufficiently above the restricted portion of the bottle neck and within the enlarged portion thereof as to provide a cavity into which, in the rare event of the 25 formation of slivers or splinters, these slivers or splinters may fall or be forced by the contracting action of the surrounding resilient sleeve and the provision of a shoulder upon which the ferrule seats itself both to determine the position of 30 the cork and to provide a positive stop for the stopper, thereby positively locating the upper face of the stopper at a predetermined point in the bottle neck.

Other important features of the invention to 40 which specific reference has not been made hereinabove are the provision on the outside of the bottle neck of a rib or bead extending both above and below the ferrule-supporting shoulder hereinabove referred to and having the important 45 functions of facilitating the casting of the inside shoulder, providing reinforcement of the neck structure at this point and serving as a retaining device for the resilient covering member, as hereinafter indicated; the tapering of the outer 50 side face of the removable portion of the bottle neck in such manner that the resilient covering member tends to lift the removable section away from the part integral with the bottle, immediately upon rupture, thereby preventing any tendency of the two ruptured faces to grind against 55 each other when the bottle user starts to pull the removable section out of the surrounding covering; the formation of a bead or rib upon the upper margin of the bottle neck to permit 60 the formation of a shoulder for the seal by which the bottle is rendered tamper-proof, and the provision of indicia by which the rupture-initiating slot may be located to permit the ready insertion 65 of the key through the covering member into the slot.

While I have discussed generally the subject-matter of my invention and the means embodied therein, it will readily be understood that there 70 are other features which will be apparent after study of the detailed description of the invention and which I may refer to incidentally in the detailed description. For the detailed description I will refer to the accompanying drawing wherein

Figure 1 is an elevation of the invention applied to the neck of a bottle;

Figure 2 is a section through the bottle neck of Figure 1 showing the use of the rupture-initiating key;

Figure 3 shows the bottle neck and its covering after the upper portion has been broken off;

Figure 4 is an elevation of the broken off upper portion;

Figure 5 is a section of the slot-engaging part 10 of the key shown in Figure 2;

Figure 6 is a detailed section showing the mode of operation of the key;

Figure 7 is a section of the bottle neck showing 15 the slot cut therein;

Figure 8 is an elevation of the resilient sleeve member forming a part of the illustrative embodiment of my invention;

Figure 9 shows a modification of the means 20 for indicating the location of the slot.

Referring now more particularly to the drawing, reference numeral 10 indicates the neck of a bottle, the construction of which is best illustrated in Figure 2. Into the restricted portion of that part of the bottle neck which is to remain a permanent part of the bottle, is inserted the hollow cork 11 provided with a ferrule 12 which abuts against a shoulder 13 and limits the inward movement of the cork 11. The cork 11 is, however, preferably long enough so that it extends downward into the bottle beyond the most restricted portion of the neck in order to expand into an enlarged portion and thus resist too easy removal. The ferrule 12 preferably extends over the upper edge of the cork 11 and thus provides 25 an abutment for the head 16 of a stopper 15 which may be made of porcelain or any other suitable material and which serves with the cork to provide an effective closure of the bottle and convenient access to its contents when the removable portion of the bottle neck hereinafter to be described has been broken away from the permanent structure of the bottle.

The bottle neck above the shoulder 13 is of such 30 inside dimensions that a space is preferably provided between the ferrule 12 and the inner wall of the bottle neck to prevent the rupturing of the removable portion of the bottle neck from the permanent structure from interfering with the main bottle closure and to prevent the cork and 35 its surrounding ferrule 12 and the stopper 16 from interfering with the rupturing action. As shown in the drawing, the inner wall of the part of the bottle neck above the shoulder 13 tapers uniformly up to the shoulder or seat 34 hereinafter 40 to be described.

The bottle neck is sealed above the stopper head 16 to prevent access thereto, except by breaking off the upper part of the bottle neck in the manner hereinafter to be described, in the 45 following manner:

Above the head 16 of the stopper 15 is placed a fibrous washer member 17 which supports a layer of cement 18 while the same is hardening, the cement being of a type having the same acid-resisting properties as glass so that it cannot be removed by acids without at the same time showing, by injury to the bottle neck itself, that the bottle has been tampered with. The cement 18 also serves to lock in position a cap 19 which 50 may be made of metal or any other suitable material. If desired, the cap 19 may also be made of glass. The shoulder or seat 34 provided in the upper end of the bottle serves two purposes,—it 55 serves to locate the cap 19 and also to provide an 60

abutment which prevents any possibility of working a tool past the cap to the under side of the layer of cement 18.

It will be understood that the fibrous member 17 serves both to prevent the dropping of the cement below the desired level, in other words, as a bottom form for the molding operation, and at the same time acts as a cushion between the stopper head 16 and the cement layer 18, when set, so that such pressure as would normally be exerted on the stopper 16 either by expansion of the bottle contents or by expansion of the cement would not cause undesirable strains, interfering with an easy rupturing or ripping action, but 15 would be taken up by the yielding of the cushion 17. Expansion in the chamber formed in the upper part of the bottle neck itself will vent itself through the slot hereinafter to be described. A pressure-relieving space 20 is also preferably 20 provided between the upper surface of the cement layer 18 and the sealing member 19.

As I have indicated hereinabove, the bottle is molded into its final shape, with the exception of the formation of the slot, and thoroughly annealed before the rupture-initiating slot is formed. This slot is then formed by cutting, the bottle neck being placed in a suitable cutting machine, for example, one provided with a rubber bound abrasive wheel which cuts a groove 21 in the neck 30 10, as is best shown in Figure 7.

This groove or slot, as shown in Figure 7, preferably extends through both surfaces of the bottle neck,—both the outer and inner surface,—so that the cleavage plane thus initiated extends 35 through both bottle surfaces in which the strains have been substantially uniformly distributed by means of the annealing operation. This creates what is sometimes designated as a weak section which has essentially a tendency to fracture, 40 when spreading pressure is brought to bear upon the walls of the slot or groove 21, in a plane across the bottle neck coinciding substantially with what may be designated as the plane of the groove or slot 21. It will also be noted that any spreading 45 pressure brought to bear against the walls of the slot will first act against the sharply tapered portions of the remaining neck section and then against the full neck cross section.

In addition, the groove or slot 21 is preferably 50 cut so that its plane is substantially normal to the axis of the bottle neck and therefore the cleavage plane will be substantially normal to the bottle neck. The slot 21, however, having substantial width, it is found in practice, possibly 55 by reason of the fact that the pressure upon the two sides of the slot is not exerted in the same vertical plane, that the rupturing action starts in two planes slightly offset from each other but both normal to the axis of the bottle neck, these 60 planes being close enough together so that the offset rupture necessary to connect them forms without any tendency to shatter the glass.

Figure 5 illustrates the spreading section of the key 22, this section being denoted by the reference numeral 23.

Figure 6 illustrates the action of the section 23 in the slot 21. It will be observed that during the major rotation of the portion 23 within the slot 21 it does not exert any substantial spreading 70 force on the two walls of the slot. During the last part of its movement it acts to separate the upper and lower walls, this spreading action being substantially parallel to the axis of the bottle neck. This exertion of a steady vertical pressure 75 separating the two walls of the slot effects a pro-

gressive fracture of the bottle neck, starting from each tapered end of the slotted section, which might be compared to a ripping action and which proceeds without the formation of slivers or splinters of glass. It should be emphasized here that the substantial height of the portion 10a of the removable neck is intentionally provided for. The portion 10a must be rigid and unyielding in order that a real ripping action be obtained along the axis of the slot. The substantial height of 10 portion 10a contributes this rigidity.

It will be noted that the slot 21 is cut in the bottle neck substantially at the line of junction of the enlarged rib or bead portion 14 of the neck with the upper part of the neck, and it is important that the cleavage plane initiated by this slot be substantially coincident with the plane of this line of junction. To insure this with absolute accuracy, definite relationships are established between the top of the bottle neck and the various other features characterizing this invention, such as the location of the bead 14, the shoulder 12, etc. and therefore, when cutting the slot 21, the cutting tool may be given its cutting location by reference to the top of the bottle neck as, for example, by a suitable gage resting against said top. At this point it will be well to indicate also that the bottle neck is tapered outwardly both upwardly and downwardly from the slot. This tapering is, I have found, very important in confining the severing to the plane of the slot 21, upon action of the tool.

In connection with my invention and constituting a part thereof in the preferred embodiment, I employ a resilient rubber sleeve member 25 which has a series of functions. In the first place, it is very important that bottles be so constructed that they may be filled by recently devised vacuum filling systems. My sleeve 25 serves as shown in Figure 1, to close the slot 21 and thus to permit vacuum filling of the bottle, the closing by the sleeve being substantially a sealing action. Although the rupturing action, which separates the upper half 10a of the bottle neck from the permanent bottle structure, takes place consistently and almost without exception without the formation of any splinters or slivers of glass, in order to insure against possibly defectively annealed bottles, the sleeve 25 extends sufficiently above the cleavage plane so that if splinters or slivers of glass should be accidentally formed they will be prevented from flying away from the bottle or from being left in such a position that they could in any way mix with the contents of the bottle.

As best illustrated in Figure 2, the sleeve 25 is so placed that it must be pierced by the key 22. Naturally the outward movement of the key after it has performed its spreading function will permit the resilient member 25 to wipe off the blade 23. When the upper portion 10a is then pulled upward, the shape of the sleeve and the shape of this portion initiating a short separating movement at the time of rupture, the upper bead 26 of the sleeve will snap inward against the ferrule 12, thereby forming a pocket into which any slivers or splinters of glass that, in a rare event, might accidentally be formed would be forced and confined, the bead 26 and the immediately adjacent portions of the resilient member 25 forming a shield over the section 27 of the rupture, as will be quite apparent. It will also be quite apparent that the bead or rib 14 of the neck will serve to maintain the sleeve 25 in the position shown in Figure 3, the sleeve 25 being also pref-

erably provided with a bead on its lower edge to reinforce the resiliency of the sleeve at that point.

In view of the description just presented, it will be quite obvious that the sleeve 25 serves to 5 permit vacuum filling, to wipe off the severing or spreading key as it leaves the severed section, to cover the point of rupture or severance at the time of the severing action, to snap over the rough or severed section to cover the same 10 when the severed portion is removed and to form a pocket with the ferrule to receive fragments of glass in the very rare event that any should be formed.

In order to indicate the position where the 15 cutting end of the blade 23 of the key is to pierce the covering member 25, a colored dash 28 may be imprinted on the member, as best shown in Figure 1. The vertical plane of the cutting position will preferably be indicated by 20 an arrow 29 molded into the bottle neck.

In Figure 9 I show a modified form of the covering member 25 in which the lower bead 30 of the sleeve 25 extends downwardly against a bottom shoulder 31 on the neck, which serves 25 to facilitate the proper location of the sleeve on the bottle neck and to insure its maintenance in such location. I also show a modified form of indicating means comprising a pair of lugs 30 32 molded integral with the bottle neck and serving to press outwardly a portion of the member 25, thereby to indicate the position of the slot 21.

It is also to be noted that, in all forms of the invention, the slot 21 and the shoulder 13 are 35 so offset vertically that, in the event that slot 21 should carelessly be cut in a plane slightly inclined to the axis of the neck, the cleavage plane will not run below the shoulder 13, with the possibility of a sharp edge of the removable part 40 10a engaging and tending to pull out the cork 11.

The term "rupturing" has been used throughout the specification and in some of the claims to describe the breaking, fracturing or severing action which takes place when the key operates 45 to remove the removable part of the bottle neck, the term rupturing having been selected as possibly more accurately descriptive of what actually takes place. As I have pointed out above, the parting of the two parts of the bottle takes place 50 by a progressive movement starting at each tapered end of the slot 21 and is more analogous to a ripping action than the usual fracturing action that takes place when glass is cut. This possibly explains the complete absence of splinters, slivers, flakes or chips of glass in the ordinary operation of opening the bottle.

While I have shown and described a particular embodiment of my invention, I believe that I have made a relatively broad contribution to the 60 art in the field in which I am working. I feel entitled, therefore, to claims of the scope of those hereto appended.

This application as to common subject-matter is a continuation of my application Serial No. 65 738,953, filed August 8, 1934, for Letters Patent for improvements in Bottle locks.

I claim:

1. A bottle of the class described having a neck, said neck having a slot the walls of which 70 present shearing edges at the outer surface of the neck and into which slot a tool may enter to exert a force to rupture the neck substantially along the axis of said slot, a covering member for said slot having a penetrable area between 75 said shearing edges, and adapted to be penetrated

by said tool when it is moved against said area and into said slot.

2. A bottle of the class described having a neck, said neck having a slot into which a tool may enter to exert a force to sever the neck substantially in the plane of said slot, a hollow cork fitted into a portion of the neck below said slot, a shoulder on the neck, a ferrule on the cork adapted to impinge against the neck shoulder to determine the depth of insertion of the 10 cork, that portion of the neck above said shoulder being of such size as to leave a space between the neck and ferrule, said slot being located above the neck shoulder.

3. A bottle of the class described having an 15 outer neck, said neck having a slot into which a tool may enter to exert a force to sever the neck substantially in the plane of said slot, a pouring neck in the inside of said bottle and substantially coextensive with said outer neck, said 20 slot being located in a portion of the outer neck opposite said pouring neck but below its pouring end, and a resilient member arranged about said neck and adapted to snap over the slotted and severed sections of the neck and against 25 the surface of the pouring neck after the tool has operated and as the severed neck portion is removed.

4. A bottle of the class described having an outer neck, said neck having a slot into which 30 a tool may enter to exert a force to sever the neck substantially in the plane of said slot, a pouring neck in the inside of said outer neck, substantially coextensive with said outer neck, and having a pouring end extending above the 35 slot in the outer neck, and a resilient member arranged about said outer neck for piercing by a tool entering said slot and adapted to snap over the slotted and severed sections of the outer neck and against the inner pouring neck after 40 the tool has operated and the severed neck portion is removed, the resilient member being so formed, and the neck portion on which it is mounted being so shaped, that the said resilient member is maintained in constant tension but 45 is restrained against creeping upwardly on said neck, while adapted to snap against the inner pouring neck when the severed neck portion is removed.

5. A bottle of the class described having an 50 integral outer neck permanently sealed, an inside pouring neck substantially coextensive with said outer neck, removable closer means for said inside neck inaccessible while said outer neck is integral and sealed, said outer neck having a slot 55 into which a tool may enter to exert a force to sever the neck substantially in the plane of the slot, and a resilient member fitted about said outer neck for piercing by a tool entering said slot and adapted to snap over the slotted and 60 severed sections of said neck after severance thereof and removal of the severed portion incidental to rendering said inside pouring neck and closure accessible.

6. A bottle neck for the purposes described 65 comprising a portion having a substantially cylindrical passage and a top portion having a concentric passage of greater diameter, the inner wall of the top portion being abruptly offset from the inner wall of the first-mentioned portion to form a seat for an inner dispensing neck, an inner dispensing neck in said top portion and seated on said seat, said top portion having a rupture initiating cut extending through 70 75

the wall thereof in a plane above said seat and substantially parallel thereto.

7. A bottle neck for the purposes described comprising a portion having a substantially cylindrical passage and a top portion having a concentric passage of greater diameter, the inner wall of the top portion being abruptly offset from the inner wall of the first-mentioned portion to form a seat for an inner dispensing neck, 5 said top portion having a rupture initiating cut extending through the wall thereof in a plane above said seat and substantially parallel thereto, a resilient guard covering said cut and of such initial configuration that it moves into covering 10 relation to the face and edges of the fracture on the permanent neck structure when the removable top portion is severed therefrom to render 15 said inner neck accessible.

8. For rupturing a bottle having a rupture 20 plane determining slot cut through a segment of the neck thereof in a plane substantially normal to the axis of the neck, and a resilient shield about said bottle neck covering said slot and of such resiliency that it will contract over and shield 25 the surface of the fracture on the permanent neck structure when the removable section has been broken off, a key having a sharp end constructed to piece said shield and freely enter said slot in one position, and a section constructed 30 to spread the walls of said slot when turned thereafter.

9. In a bottle of the class described, a bottle 35 neck having concentric inner and outer surfaces, said neck having a slot cut through said surfaces with the angular extent of the slot on the outer surface greater than the angular extent of the slot on the inner surface, whereby to leave a neck section terminating in sharply tapered portions for the purposes described.

10. A bottle having a neck with a slot therein adapted for the insertion of a tool medially thereof to apply rupturing pressure against the walls of the slot, the slot being so formed that the remaining section of the neck to be ruptured terminates at each end in points sharply tapered and with said points forming the portions of the remaining neck structure nearest the medial point of the slot at which rupturing pressure must necessarily be applied by said tool, whereby rupturing pressure will first be applied at said opposite sharply tapered points and then progressively therefrom until the bottle neck is ruptured by a progressive substantially ripping action. 16

11. A bottle neck having a rupture determining 15 slot cut therein and traversing entirely the wall of said bottle neck, said neck tapering gradually for a substantial distance upwardly and outwardly from said slot.

12. A bottle neck having a rupture determining 20 slot cut therein and traversing entirely the wall of said bottle neck, said neck tapering upwardly and outwardly from said slot, the upper portion of the neck above the slot being of substantial height so as to form a relatively rigid 25 body.

13. The method of breaking a bottle neck equipped with a slot and a resilient covering about the neck and covering said slot, which comprises inserting a sharp tool through the said covering 30 and into the slot, and manipulating the tool in said slot to exert a pressure to rupture the neck, whereby the severing of the neck will be accomplished in a covered and protected zone while the tool will necessarily be wiped when removed 35 from the slot.

LESTER P. BARLOW.
